UNITED STATES PATENT OFFICE.

LOUIS McCARTHY, OF BOSTON, MASSACHUSETTS.

DESIGN FOR A TRAY.

SPECIFICATION forming part of Design No. 32,284, dated February 27, 1900.

Application filed December 1, 1899. Serial No. 738,916. Term of patent 14 years.

To all whom it may concern:

Be it known that I, LOUIS McCARTHY, a citizen of the United States, residing at Boston, in the county of Suffolk, State of Massachusetts, have invented a certain new and original Design for Trays, of which the following is a specification, reference being had therein to the accompanying drawings.

Figure 1 is a perspective of a tray, showing my design, the sides of the tray being shown in dotted lines. Fig. 2 is a plan of Fig. 1.

My design has reference more especially to the tray-bottom, and, as shown in the drawings, the leading or material features of my design consist of a series of inclined ribs 1 on the bottom 2, which extend from opposite sides of the tray, pointing inwardly at right angles with the edges 4, the ribs being trian-

gular in cross-section, with the inclined faces 3 at right angles with each other. In longitudinal section the ribs are triangular, the ridge-line 5 being the longest side of the triangle, which tapers down to a very acute angle at the inner end thereof. The sides of the tray are indicated in dotted lines.

Having described my invention, what I claim as new, and desire to secure by Letters Patent, is—

The design for a tray, as herein shown and described.

In testimony whereof I affix my signature in presence of two witnesses.

LOUIS McCARTHY.

Witnesses:

W.M. A. MACLEOD,
ALICE H. MORRISON.
